UNITED STATES PATENT OFFICE.

WILLIAM J. COSTELLO, OF PENN TOWNSHIP, ALLEGHENY COUNTY, PENNSYLVANIA,
ASSIGNOR OF ONE-HALF TO JOSEPH E. KATZ, OF VERNON, PENNSYLVANIA.

ANTICREEPING CLAMP.

Application filed September 9, 1922. Serial No. 587,063.

To all whom it may concern:

Be it known that I, WILLIAM J. COSTELLO, residing at Penn Township, in the county of Allegheny and State of Pennsylvania, a citizen of the United States, have invented or discovered certain new and useful Improvements in Anticreeping Clamps, of which improvements the following is specification.

The invention described herein relates to what is sometimes termed "anti-creepers" for rails, i. e., devices secured to rails intermediate the cross-ties and adapted to bear against the latter to prevent material movement of the rail on the cross-ties and to maintain a proper spacing of the latter. The invention has for its object a construction employing two hook-shaped members, one having a resilient element and the other a finger which when the two members are applied to the flange of a rail, will force the spring element against the underside of the rail flange. It is a further characteristic of the improvement that the hooks are so constructed that the free end of the hook will bite on the upper surfaces of the flanges. The invention is hereinafter more fully described and claimed.

In the accompanying drawing forming a part of this specification, Fig. 1 is a sectional elevation of a rail having the improved anti-creeping device applied thereto; Fig. 2 is a side elevation of a rail and a cross-section of a cross-tie, the rail having the improved device applied thereto; Fig. 3 is a view of the underside of a rail and showing the device in position thereon.

In the practice of the invention one member A consists of a hook so constructed that the body portion 1 will bear on the underside of the flange of the rail while the other leg 2 of the hook is so shaped that it will bear at its end on the upper surface of the flange. The extension of the body portion is bent to form a ring 3 and has a portion 4 extending tangentially from the ring. By reference to Figs. 1 and 2 it will be seen that the finger or portion 4 is in the plane of the body portion 2 so that when the member A is placed in position on the rail flange, the finger 4 will bear against the underside of the flange.

The other member B consists of a hook so

constructed that the free end or portion 5 will bear at its end on the upper surface of the rail flange, while the body portion 6 and its extension 7 will be at such an angle to the part 5 that when the hook is being placed in position, the extension or expanding prong 7 will pass through the ring 3 of the other member without any tendency to force such member out of position.

It is preferred that the members should be square in cross-section except the prong which is made round so as to fit into the ring. This prong has its end a little smaller than the inner diameter of the ring so as to facilitate its insertion, and increases in diameter so that when the member B is driven to position, the ring will be expanded and the finger 4 caused to bear tightly against the underside of the rail flange.

It will be observed by reference to Fig. 2 that the device is so applied that the ring 3 will bear against the cross-tie and hence in case of movement of the rail in the direction of the arrow *a* the pressure of the device against the cross tie will tend to force the device along the rail in the direction of the arrow *b*. When the prong is forced into the ring it will cause an expansion of the ring and such a movement of the end of the finger 4 as to cause it to bite into the rail and prevent a movement of the device relative to the rail. It will be observed that the portions 2 and 5 of the members A and B bear at their ends on the upper faces of the rail flanges; as these portions of the devices are made square, corners will bite into the rail when pressure is applied, as before described, to the ring, such pressure tending to move the devices to an angular position relative to the rail.

I claim herein as my invention:

1. Means for preventing the creeping of rails having in combination a hook adapted to engage a flange of a rail and the part extending under the rail provided with a resilient finger, a second hook also adapted to engage the rail flange and provided with a prong adapted to force the resilient finger into engagement with the underside of the rail flange.

2. Means for preventing the creeping of rails having in combination a hook adapted

to engage a flange of a rail, the part of the hook extending under the flange being bent to form an open ring and having a tangential extension forming a finger adapted to bear on the underside of the rail, in combination with a second hook adapted to engage a rail flange and having a tapering prong

adapted to be forced into the ring of the other hook and expand the ring whereby the finger is caused to bear firmly on the underside of the rail. 10

In testimony whereof, I have hereunto set my hand.

WILLIAM J. COSTELLO.
